CLAIM

The ornamental design for a display screen with graphical user interface as shown and described.

DESCRIPTION

The FIGURE is a front view of a display screen with graphical user interface showing the claimed design.

The outer dashed broken lines in the FIGURE show a display screen, and form no part of the claimed design.

The dot-dash broken lines in the FIGURE and the areas within the dot-dash broken lines form no part of the claimed design.

The other dashed broken lines in the FIGURE show portions of the graphical user interface that form no part of the claimed design.

The FIGURE is illustrated to show contrasting appearance. Areas of the display screen with graphical user interface that appear in different shades of gray and black represent areas with contrasting appearances. Areas that appear in white form no part of the claimed design. No particular color is claimed.
